UNITED STATES PATENT OFFICE.

WILLIAM ILE, OF JACKSON, MICHIGAN, ASSIGNOR TO REYNOLDS SPRING COMPANY,
OF JACKSON, MICHIGAN, A CORPORATION OF DELAWARE.

TABLE TAP.

Application filed May 6, 1926. Serial No. 107,283.

The invention relates to a table tap.

The object of the present invention is to provide a simple, practical and efficient table tap of strong, durable and comparatively inexpensive construction equipped with a plurality of outlets and adapted to have one of the outlets connected with a floor plug or other feed connection and capable of providing for a plurality of independent circuits for lighting Christmas trees and also for analogous uses such as supplying current to a lamp and a plurality of electrical appliances.

Another object of the invention is to provide a table tap of this character which may be safely left connected with an outlet box without liability of a person coming in contact with the terminals or contacts of the table tap.

Another object of the invention is to provide a table tap equipped with concealed fastening means for securing the parts together so that there will be no liability of the table tap being accidentally taken apart while connected with an outlet box, floor plug or the like.

With these and other objects in view, the invention consists in the construction and novel combination and arrangement of parts hereinafter fully described, illustrated in the accompanying drawings and pointed out in the claims hereto appended, it being understood that various changes in the form, proportion and minor details of construction, within the scope of the claims, may be resorted to without departing from the spirit or sacrificing any of the advantages of the invention.

In the drawings:—

Figure 1 is a side elevation of a table tap constructed in accordance with this invention.

Fig. 2 is a longitudinal sectional view of the same.

Fig. 3 is a sectional view taken substantially on the line 3—3 of Fig. 2.

Fig. 4 is an elevation of the body portion of the table tap.

Fig. 5 is a plan view of the insulating closure disk.

Fig. 6 is a longitudinal sectional view of the body of the table tap.

Fig. 7 is a perspective view of one of the multiple spring contacts.

Fig. 8 is a sectional view taken substan-

ti ally on the line 8—8 of Fig. 4 illustrating the manner of mounting the multiple spring contacts.

In the accompanying drawing in which is illustrated the preferred embodiment of the invention the table tap comprises in its construction a hollow insulating body consisting of a shell composed of a single piece of molded insulating material such as Bakelite open at one side or end at 2 to afford access to its interior and provided at its other three sides with circular faces 3, 4 and 5 forming seats for cap sections 6, 7 and 8. The open end is normally covered by a closure disk 9 of insulating material having secured to it a cap section 10. The closure disk and the cap sections are constructed of the same material as the body of the table tap and the cap sections are substantially the same construction and each is provided with spaced knife contacts 11 formed integral with plates 12 secured to each of the cap sections and provided with binding screws 13 for the attachment of wires 14 of a cord 15. Each of the cap sections is of like construction and detailed illustration of only one of the same is deemed necessary and complete sectioning of the other cap sections is omitted for convenience of illustration.

The closure disk 9 is secured to the cap section 10 by screws 16 which engage threaded apertures 17 in the plates 12 of the knife contacts of the section 10. Each of the circular faces 3, 4 and 5 are provided with a marginal flange or rib 18 as shown and the cap sections 6, 7 and 8 fit against the same. The closure disk is secured to the body 1 by means of a longitudinal screw 20 engaging an interiorly threaded bushing 21 embedded in the closure disk at the center thereof and preferably surrounded at the inner face of the disk by an annular boss 22. The screw extends through a central opening 23 in the side or face 3 of the body and is provided with a head which is sealed in a countersink or recess 24 in the center of the side or face 3 of the body. After the screw is placed in position and is screwed tightly in engagement with the bushing of the closure cap the head of the screw is concealed in the countersink or recess 24 by a filling 25 of cement or other suitable plastic material. This will prevent the head of the screw from being seen when

the cap section 6 is removed and there will be no temptation for anyone to remove the screw 20 and separate the cap section 10 and thereby expose the knife contacts. This 5 will eliminate any danger to persons from leaving the cord 15 connected to a floor plug outlet box or other feed connection and the table tap will always afford a plurality of feed connections. The sides or faces 3, 4 10 and 5 are provided with spaced slots 26 for the passage of the knife contacts of the cap sections which may be readily plugged into the body or removed therefrom at will and the said body is equipped at its interior 15 with multiple spring contacts for engagement with the knife contacts.

Each multiple spring contact which is arranged in the form of a cross consists of two springs 27 and 28 of suitable conducting 20 metal centrally secured together by a tubular rivet 29 or other suitable fastening device and having their outer portions bent backwardly upon themselves to form four substantially U-shaped spring contacts as clearly 25 illustrated in Fig. 7 of the drawings. The rivet 29 also pierces a supporting bar 30 extending longitudinally of the rear face of one of the strips and having projecting terminals 31 which when the parts are assembled fit respectively in recesses 32 and 33 of the body and the closure disk 9. The recesses 32 are formed in the inner face of the side or end 3 and are arranged directly opposite or in alignment with the recesses 33. 30 The shell is provided at its inner face with opposite longitudinal grooves 34 which facilitate the assembling of the multiple spring contacts and which also receive lugs 35 formed integral with the closure disk and 40 interlocking the latter with the shell or body. When the terminals 31 of the supporting bars 30 are fitted in the recesses 32 and 33 of the body and the closure disk the multiple spring contacts are firmly held in position 45 without employing fastening devices for securing the spring contacts to the body. This will enable the spring contacts to be readily assembled or removed and materially lessens the cost of the construction and at 50 the same time effectively prevents any displacement of the spring contacts due to a loosening of fastening devices.

What is claimed is:

1. A table tap comprising a hollow body 55 of insulating material consisting of a shell open at one end and provided at the other end and at opposite sides with seats for cap sections and having spaced slots to receive knife contacts of the same, a closure disk of 60 insulating material covering the open end of the body and provided with slots and having an interiorly threaded bushing embedded in it, a screw extending through the body and engaging the said bushing and securing the 65 closure disk to the body, a cap section se-

cured to the closure disk and having knife contacts extending through the slots thereof and contacts arranged within the body and engaged by the knife contacts.

2. A table tap comprising a hollow body 70 of insulating material consisting of a shell open at one end and provided at the other end and at opposite sides with seats for cap sections and having spaced slots to receive knife contacts of the same, a closure disk of 75 insulating material covering the open end of the body and provided with slots and having an interiorly threaded bushing embedded in it, a screw extending through the body and engaging the said bushing and securing the 80 closure disk to the body, said screw having its head countersunk in the body, a plastic filling covering the head of the screw and concealing the same, a cap section secured to the closure disk and having knife contacts 85 extending through the slots thereof, and contacts arranged within the body for engaging the knife contacts of the cap sections.

3. A table tap comprising a hollow body 90 of insulating material consisting of a shell open at one end and provided at the other end and at opposite sides with seats for cap sections and having spaced slots to receive knife contacts of the same, a closure disk of 95 insulating material covering the open end of the body and provided with slots and having an interiorly threaded bushing embedded in it, a screw extending through the body and engaging the said bushing and securing the closure disk to the body, a cap section fitted against the closure disk and having knife contacts extending through the slots thereof, screws piercing the closure disk and securing the cap section to the same and having their heads arranged at the inner 100 face of the said closure disk, and contacts arranged within the body and adapted to be engaged by the knife contacts of the cap sections.

4. A table tap comprising a hollow body 110 of insulating material open at one end and provided at the opposite end with interiorly arranged recesses, said body also having closed sides provided with slots to receive knife contacts of cap sections, a closure disk of insulating material covering the open end of the body and provided with recesses arranged opposite the said recesses, means for securing the closure disk to the body, and multiple spring contacts arranged within the body and provided with supporting bars having their terminals fitted in the said recesses whereby the multiple contacts are held in position.

5. A table tap comprising a hollow body 125 of insulating material open at one end and provided at the opposite end with interiorly arranged recesses, said body having closed sides provided with slots to receive knife contacts of cap sections, a closure disk of 130

- insulating material covering the open end of the body and provided with recesses arranged opposite the said recesses, means for securing the closure disk to the body, multiple spring contacts arranged within the body and provided with supporting bars having their terminals fitted in the said recesses whereby the multiple contacts are held in position, and a cap section secured to the closure disk and having knife contacts extending through the same and engaging the spring contacts.
6. A table tap comprising a hollow body of insulating material open at one end and provided with interiorly arranged grooves extending inwardly from the open end of the body, a closure disk of insulating ma-
- terial covering the open end of the body and provided with lugs fitting in the said grooves and interlocking the closure disk with the body, a screw extending through the body centrally thereof and securing the closure disk to the body, and multiple spring contacts arranged within the body and provided with supporting bars having their ends interlocked with the closure disk and with the opposite end of the body, the latter being provided with slots arranged in line with the spring contacts, the said spring contacts and the supporting bars being spaced from the said slots.
- In testimony whereof, I have hereunto set my hand.

WILLIAM ILE.
